CLAIM

The ornamental design for an entertainment venue, as shown and described.

DESCRIPTION

FIG. 1 is a front-perspective view of an entertainment venue in accordance with the design;

FIG. 2 is a front-elevation view thereof;

FIG. 3 is a rear-elevation view thereof;

FIG. 4 is a right-side view thereof;

FIG. 5 is a left-side view thereof; and,

FIG. 6 is a top-plan view thereof.

Any broken lines present in the drawings are for illustrative purposes only and form no part of the design to be patented.
